UNITED STATES PATENT OFFICE.

CLIFFORD C. CHURCH, OF GRAND RAPIDS, MICHIGAN.

COLLAPSIBLE CUT-OUT TOY.

1,111,216.

Specification of Letters Patent. Patented Sept. 22, 1914.

Application filed October 28, 1913. Serial No. 797,862.

To all whom it may concern:

Be it known that I, CLIFFORD C. CHURCH, a citizen of the United States, residing at Grand Rapids, Michigan, have invented certain new and useful Improvements in Collapsible Cut-Out Toys, of which the following is a specification.

The present invention relates to an improved collapsible toy having the form of a vehicle preferably with horses harnessed thereto. It is designed to be made of linen, paper, cardboard, tin, or other suitable material to be printed, lithographed or otherwise decorated in different designs, and the main parts thereof constructed of single pieces forming blanks. These blanks can be manufactured and sold in sheet form only adapted to be cut out by the purchaser, or can be sold already cut out, folded and set up, in which form an attractive novelty is provided which can be used as a toy or serve as a display article for advertising purposes.

The invention comprises the provision of several blanks in sheet form so marked and decorated that they can be cut out and folded as indicated by marks or scorings and interlocked in such a manner as to present when assembled a vehicle with wheels or sleigh runners.

The invention further comprises the provision of blanks in single sheet form or separately so marked and decorated that they can be cut out, folded as indicated by the marks thereon, and connected together by interlocking the various parts, in such a manner as to present when assembled a vehicle or sleigh with a team of draft animals such as horses, oxen, mules or one or more like figures harnessed thereto.

With these and other objects in view, the invention consists in the construction and arrangement of parts, more fully set forth in the following specification, illustrated in the accompanying drawings and pointed out in the appended claims.

In the drawings:—Figure 1 is a view representing the blank from which the horses and their supporting platform are made. Fig. 2 is a view representing the blank from

which the neck-yoke, collars and traces of the horses' harness is formed. Fig. 3 is a view representing the blank from which the wagon tongue, wheel axles and body supports are constructed. Fig. 4 is a view representing the blank from which the wagon wheels and their supporting platform are made. Fig. 5 is a view representing a blank from which the main body portion of a delivery wagon, including top, bottom, sides, front and rear portions, are formed. Fig. 6 is a view representing a modified form of blank from which a piano box buggy and top is constructed. Fig. 7 is a perspective view showing the various blanks illustrated in Figs. 1, 2, 3, 4 and 5 cut out, folded and assembled to present the toy in its complete and finished form. Figs. 8 and 8^a illustrate a modification in which the wheels are connected together and to the body solely through their hub portions; and Fig. 9 illustrates the use of sleigh runners instead of wheels; and Fig. 10 is a view of a further modification.

Referring now to the drawings, wherever a tab is illustrated on one member and designated by a reference character, a corresponding slit or opening is provided and similarly designated by the same reference character on another member, which latter member is designed to connect with the first mentioned member when the parts assume their assembled form. The dotted lines in every instance indicate a guide to be followed in folding the blanks, which may be scored or weakened to facilitate folding.

In Fig. 1, the horses (shown as representative of any animals) 2 and 3 are shown connected to their supporting base which comprises two members A and B integral with each other. In assembling this blank the horses 2 and 3 are folded to a vertical position at right angles to the portion A, the part B is then folded back at the line a—a, through 180 degrees so that A assumes a superimposed position on B. The tab 1 of A is then inserted in the slit 1^a of B and the tab 1 of A and tab 1^b of B (portion on right of line b—b) together bent slightly 100

upward along the lines $a'-a'$ and $b-b$. This forms a slightly upturned forward edge which will readily glide over any small edge which that part of the toy 5 may come in contact. A string is passed through the holes a^x and b^x which register the one with the other and by this means the toy can be pulled along. By having the main platform B of sufficient size to fold 10 under the portion A, the proper weight and support for the horses is attained. This weight is necessary in order to make the blank for the horses of the same weight material as the vehicle blank is made from.

15 The blank shown in Fig. 4 is folded in a similar manner. The body supports (here shown as wheels) are bent up to vertical position at right angles to the base portion C with which they are integrally formed. 20 The base portion C is provided with a tab C' adapted to be bent slightly upward at the line $c-c$ which serves the same purpose as the upwardly inclined portion of the base of Fig. 1.

25 The blank shown in Fig. 5 contains the top, bottom, sides, front dash and rear door of the wagon. The sides E-E are folded along the dotted lines $e-e$, $f-f$, in such manner as to assume a vertical position at 30 right angles to the top member D. The main bottom of the wagon F is then folded along the line $g-g$ until it assumes a position parallel to the top and at right angles to the side E to which it is attached. The tabs E', E² are similarly folded along the lines $h-h$ and $i-i$ and these members assume a position directly under the main bottom F. The slits 7', 7'' of the tab E' and the main bottom F will thus register, as will 35 also the slits 8', 8'' of the tab E² and the bottom. The front dash G is bent slightly upward to form the desired angle with the bottom portion F, the dotted line $k-k$ indicating where this bend occurs. The back 40 of the wagon is formed of two members L and M formed integral with the sides E, E. They are folded along the dotted lines $l-l$ and $m-m$ respectively to assume a position at right angles to the sides and bottom of 45 the wagon. The frame portion L' over the doors L, M is provided with a small tab 6 which is adapted to enter corresponding slit 6' in one of the sides E, and the door L may have a tab 1' designed to enter a corresponding slit m' in the door M. By cutting the 50 door L along the curved line at the top both of the doors will be capable of swinging to open or closed position as may be desired.

Fig. 3 illustrates the blank from which 55 the wagon tongue, wheel axles and their connecting strut are formed. The parts N and O form at the same time the support for the wagon bed and the wheel axles. They are

bent along the lines $o-o$ and $o'-o'$ to assume a vertical position at right angles to 65 the horizontal connecting brace P. The tongue T and whiffle-tree R are formed in one part connected to the forward support O. By bending along the lines $t-t$ and $s-s$ the tongue is made to assume a horizontal position parallel with the brace P and at right angles to the axle support O with which it is integral. The tabs 7 and 8 of the members N and O are bent or disposed 70 vertically.

75 Fig. 2 represents the blank from which the neck yoke, collars and traces of the horses' harness are formed. In cutting out this blank the rectangular areas designated by X and X' are cut out, leaving parallel 80 strips which form the traces of the harness. The traces Y-Y are cut along the lines $y-y$, and then folded upward on lines $z-z$ at an angle to the trace members.

85 In the several blanks cut out and folded together as has been described separately in connection with each figure, it is only necessary to assemble the parts by inserting the various tabs of one blank into the corresponding slits of the other blanks. To assemble the wagon the tabs 10 and 12 of blank Fig. 3 are inserted in the corresponding slits 10^a and 12^a of the forward wheels shown in blank 4, and similarly the tabs 9 and 11 are inserted in the corresponding 90 slits 9^a and 11^a provided in the rear wheels. The tabs, after having been inserted in their slits, may be bent one way or the other to insure a more secure locking relation of the parts. With these two blanks fitted together 95 as described, it will be seen that the wheels are maintained in a vertical position parallel to each other and the wagon tongue will be supported in its proper position parallel to the ground. The wagon body in its 100 forward position is placed upon the axle supports N and O and the tabs 7 and 8 are inserted in the alining slits 7', 7'' and 8'' of the main body F and the bottom tabs E' and E². The horses' heads 2 and 3 are next 105 inserted in the corresponding slits 2 and 3 of the collars Y-Y in such manner that the main bodies of the horses will assume and be held in a vertical position parallel to each other within the rectangular openings 110 formed by cutting out the areas X-X'. The end of the wagon tongue 13 is then inserted in the corresponding opening 13' of the neck yoke and the traces are slipped over portions R, R, which represent the whiffle-trees and which are formed integral with 115 and at the rear end of the wagon tongue.

120 Fig. 7 shows a perspective view of the wagon with horses harnessed thereto.

The blank shown and similarly lettered in Fig. 6 is assembled in essentially the same

manner and provides a vehicle body of the piano box buggy type in place of the delivery wagon form shown in Fig. 5.

If desired, I may omit the base for the 5 wheels or runners which comprise the body supports, in which event I widen out the reach into the shape of a platform with portions projecting between the wheels, as indicated at P', these projecting portions being slotted as at p' to engage the edges of the 10 wheels and thus hold them in vertical position as shown in Figs. 8 and 8a.

It will be noticed that the platform and axles are made of different width from the 15 body so that the wheels stand clear of the body, thus making the toy more nearly simulate an actual vehicle.

I have referred hereinbefore to the use of 20 runners instead of wheels as the means of supporting the body and in Fig. 9 have shown a modification using runners.

Instead of using two animals, I may use a 25 single one and a convenient manner of forming this is shown in Fig. 10 in which a horse 2^x is formed by folding the two cut out portions x and x' up against each other, the body portions being held together by a single harness member or yoke y' and the leg members being slightly spread, as shown, so 30 that the animal has the appearance of having four distinct legs and is braced thereby. In this form I prefer to provide the member A with folded over portions A' which prevents undue spreading of the animal's legs.

35 I claim as my invention:—

1. A collapsible toy comprising a plurality of separate scored and printed blanks, provided with interlocking members and adapted to be folded and fitted together, one 40 of said blanks comprising a vehicle body, another comprising vehicle running gear and a supporting base therefor, another comprising the wagon tongue and bolsters, another comprising the draft animals and a 45 supporting base therefor, and still another comprising a neck yoke and portions of the harness, substantially as described.

2. A collapsible toy comprising a plurality of separate printed blanks provided 50 with tab members, and corresponding slits, said blanks being adapted to be cut, folded and fitted together, one of said blanks being cut and scored to form the vehicle wheels and a supporting base integral therewith, another cut and scored to 55 form the wagon tongue, wheel axles and bolsters, and adapted to be detachably connected with the first mentioned blank, a third cut and scored to form the vehicle body and adapted to be detachably secured on said second-mentioned blank, a fourth blank cut and scored to form 60 the draft animals with a supporting base integral therewith, a fifth blank cut and scored

to form the neck yoke and harness for the animals, the last mentioned blank being 65 adapted to detachably couple said horses and wagon tongue blanks together by an interlocking of their parts, substantially as described.

3. A collapsible toy comprising a plurality of separate printed blanks provided with tab members and corresponding slits, said blanks adapted to be cut out and fitted together, one or more of said blanks cut to 70 form the wheels, or runners, another cut and scored to form the wagon or sleigh tongue, bolsters and step, and adapted to be detachably connected with the first mentioned blank or blanks, another cut and scored to 75 form the vehicle body and adapted to be detachably secured on said second mentioned blank, a fourth blank cut and scored to form two like figures with a supporting base integral therewith, a fifth blank cut and scored to 80 form a neck yoke, the last mentioned blank being adapted to detachably couple said figures and vehicle tongue together and in an upright position by interlocking of their parts, substantially as described.

4. A collapsible toy comprising a plurality of separate blanks, provided with tabs and corresponding slits adapted to be cut, folded and fitted together, one of said blanks to 85 form a vehicle body, another comprising two like figures and a supporting base integral therewith, another comprising a harness, and still another comprising an axle, vehicle tongue, bolsters, and fenders or steps, the last mentioned blank adapted to be interlocking with the above mentioned blanks, 90 also forming a support for attaching wheels or runners made from thin material and substantially as described.

5. A toy of the character described, comprising a base blank having the figures of 105 draft animals projecting from opposite sides thereof and foldable to vertical parallel position, and, a cut-out harness engaging such animals for holding them in parallel relation.

6. A toy of the character described comprising a figure bearing base blank having a portion doubled upon itself and interlocked at the forward edge, said interlocked portion being inclined upwardly.

7. A toy of the character described, comprising a vehicle body of sheet material having slits, body supports of sheet material having slits therein, and a member of sheet material having tabs engaging the slits in 120 the body supports and slits in the body for holding said body supports in vertical position and supporting the body therefrom.

8. A toy of the character described comprising a vehicle body of sheet material, runners or wheels constituting body supports,

and a member of sheet material having vertically turned portions provided with tongues interlocked with said body and said body supports.

5. A toy of the character described comprising a base having an upwardly inclined forward edge, body supporting members integral therewith and extending upwardly therefrom, a vehicle body, and a member

having tongues interlocking with said body ¹⁰ and body supports.

In testimony whereof, I affix my signature in presence of two witnesses.

CLIFFORD C. CHURCH.
